UNITED STATES PATENT OFFICE.

CHARLES L. BENEDICT, OF TORONTO, ONTARIO, CANADA.

ENVELOP.

1,343,075.

Specification of Letters Patent.

Patented June 8, 1920.

Application filed June 23, 1919. Serial No. 306,273.

To all whom it may concern:

Be it known that I, CHARLES L. BENEDICT, a subject of the King of England, residing at Toronto, in the county of 5 York, Province of Ontario, Canada, have invented certain new and useful Improvements in Envelops; and I do hereby declare the following to be a full, clear, and exact 10 description of the invention, such as will enable others skilled in the art to which it appertains to make and use the same.

This invention relates to improvements in envelopes and is especially directed to improving outlook or window-envelops.

15 The primary object of the invention is to provide a construction by which the postage stamp will more effectively adhere to the inclosure and by which air within the inclosure may escape. The purpose of this is 20 twofold, *i. e.*, to insure that the address on the inclosure will be held in close contact with the envelop window and to permit moisture to escape from a letter which has been press copied.

25 It has heretofore been proposed to provide envelopes with apertures through which postage stamps might project in order 30 to seal to the inclosure, but with the prior constructions, if the envelop paper is stiff or thick, said paper will have a tendency to pull the stamp away from the inclosure and consequently the inclosure will be detached from the stamp. Also 35 with the known construction, the trapped air, when the envelop is pressed, had a tendency to move the stamp away from the inclosure.

By the present improvements, the portion 40 of the envelop adjacent to the stamp aperture or apertures is slotted, so that the stamp supporting portion may yield independently of the face of the envelop to prevent accidental detachment of the stamp from the inclosure or moisture may escape 45 through the slits. With the improved envelop, the stamp will securely adhere to the inclosure at all times regardless of the stiffness or thickness of the paper, or of the air trapped in the envelop.

50 The invention consists in the novel features hereinafter described in detail in connection with the accompanying drawing and more particularly pointed out in the appended claims.

55 Referring to the drawing:—

Figure 1 is a face view of a window en-

velop having a vertical slit arranged at each side of the stamp aperture.

Fig. 2 is a similar view of a modification in which the envelop has two stamp apertures and a horizontal slit arranged above and below the apertures. 60

Fig. 3 is an enlarged section taken on the line 3—3 of Fig. 2.

In the drawing 1 represents an envelop 65 having a transparent window 2 for displaying the address on the inclosure.

In the embodiment shown in Fig. 1, the upper portion of the face of the envelop is provided with an aperture 3 through which 70 the central portion of a stamp is adapted to project and seal to the inclosure. The face of the envelop is provided with vertical slits 4, one of which is located on each side of the stamp aperture to permit the portion 5 of the envelop to be depressed with the stamp. The portion 5 is of slightly greater width than the ordinary postage stamp 6 and when this portion is depressed in attaching the stamp, air or moisture may 75 escape through the openings provided by the slits.

In Figs. 2 and 3, the face of the envelop has two stamp apertures 10 and horizontal slits 11 located above and below the apertures. 80 In this instance, the portion 12 which contains the apertures, is of slightly greater depth than the ordinary postage stamp and one or two stamps may be sealed through the apertures to the inclosure. 85

From the foregoing, it is believed that the operation will be readily understood without further description.

I am aware that various changes may be made in the constructions illustrated without departing from the spirit of the invention as set forth in the following claims. 95

What I claim and desire to secure by Letters Patent is:—

1. An envelop having an aperture through 100 which a postage stamp is adapted to be sealed to an inclosure, the envelop being provided adjacent to the aperture with a plurality of slits to provide a stamp supporting portion; which may be depressed 105 independently of the remainder of the envelop, and whereby the stamp supporting portion may yield independently of the face of the envelop to prevent accidental detachment of the stamp from the inclosure. 110

2. An envelop having one of its faces provided with a window through which

the address on an inclosure may be exhibited, said face having an aperture through which a postage stamp is adapted to be sealed to the inclosure, the envelop being slitted adjacent to the aperture to provide a stamp supporting portion, which may be depressed independently of the re-

mainder of the apertured face of the envelop, whereby the stamp supporting portion may yield independently of the face of the envelop to prevent accidental detachment of the stamp from the inclosure.

In testimony whereof I affix my signature.
CHARLES L. BENEDICT.
